UNITED STATES PATENT OFFICE.

FRANK POKORNY, OF MAMARONECK, NEW YORK, ASSIGNOR, BY DIRECT AND MESNE ASSIGNMENTS, OF ONE-HALF TO FRANCIS W. KEEGAN, OF NEW YORK, N. Y.

FLUID-CONTROL MEANS FOR MOTORS.

Original application filed May 1, 1920, Serial No. 378,190. Divided and this application filed September 18, 1924. Serial No. 738,398.

This invention relates to fluid supply control means for internal combustion engines, and my present improvements, which form the subject of this application, have been divided out from my earlier application, Serial No. 378,190, filed May 1, 1920.

While in said earlier application I have claimed certain means whereby a controlling valve is caused to open under the suction pull created by the respiratory operation of the engine, and is also subject to a drag force opposed to the lift force, it is my purpose in this divisional application to cover means for varying the degree or strength 10 of the drag force in its application to and effect upon the valve.

Other features and advantages of my invention will hereinafter appear.

In the drawings—

Figure 1 is an elevation, partly in section, of a fluid passage including my improved control means.

Fig. 2 is a partial, enlarged view of the same, but showing the device as including 25 the regulating means which are the subject of the present application.

Fig. 3 is a section on the line 3—3 of Fig. 2, and

Fig. 4 is a section on the line 4—4 of Fig. 2.

In the drawing, let 1 indicate a tube which is in communication with a carburetor (not shown), and let 2 indicate a tube which communicates with or forms part of an engine intake manifold. The tubes 1 and 2 are connected, as by flanges, 3, 4, by means of an intermediary, cylindrical casing 5, which serves as a duct or passage for the fuel mixture flowing to the engine.

In tube 1 I have shown a throttle valve 6, which however may be otherwise located. The elements of the control means, to be hereinafter described, may be snugly contained within the casing 5, that may be a casting, as by a threaded annulus 7 that is screwed 45 into the lower end of casing 5, the annulus 7 itself forming a supporting base for said elements.

In this manner, by removing the bolts 8 that unite flanges 3, 4, with the flanges 9 of casing 5, the latter, with the contained control elements may be bodily removed from its line position.

Fitting within the lower portion of casing 5, and supported on the annulus 7 is a cylindrical member having the outer concentric wall 10, the relatively shorter, inner concentric wall 11, in spaced relation with wall 10, and the concentric base 12 which is common to both walls and forms the lower closure of a concentric space or chamber 13 that is bounded circularly by said walls 10 and 11. Also the wall 11 forms the lower portion of the fluid passage to the engine.

Carried by arms 14 that are borne by the wall 11 is a centrally disposed nozzle member 15, which is provided with an axial orifice 16, for the flow of a restricted volume of fluid; and, as also shown in my said co-pending application, a concentric passage portion 17 extends up from the wall 10, carrying the 60 inwardly directed arms 18, which support a centered cone 19 in the path of the fluid ascending to the manifold.

The portion 17, which has a shoulder or under surface 20 overhanging the concentric 75 space 29, which comprises a vacuum chamber, is provided with a lower cylindrical portion 21 as part of its inner surface, said surface continuing upwardly from portion 21, at an outward inclination, to a point near the 80 upper end of portion 17, where it has a re-entrant incline.

The outer conformation of nozzle member 15 is that of a double cone, having the upper 85 conoidal portion 22, and the lower, inverted conoidal portion 23, the junction of said co-noidal portions representing the major diameter of the member 15, whose periphery, in the horizontal plane of said major diameter, co-acts with a tubular valve member 24 90 for the passage of regulated supplementary quotas of fluid in a manner to be hereinafter described.

The tubular valve 24 has an intermediary or body portion, with an upward skirt-like portion 25, and a lower, skirt portion 26, the skirt 25 extending from the most restricted diametral part of said body portion, while the skirt 26 depends from the major diametral part thereof.

It is at the most restricted diametral part of the valve body portion that said valve is contiguous to the nozzle member 15, at the major diameter thereof, because it is

the function of the valve to rise and recede from that location to thereby provide for the passage of fluid in regulated volume.

Interiorly of the said restricted diametral part of the valve body portion, the latter is given a downward and outward inclination, designated as inclined surface 27, that lies above the upper peripheral edge 11^a lies above the upper peripheral edge 11^a of wall 11. Valve 24, at the outer surface 13 of its body portion and skirt 26 is in slidable relation with wall 10, and said skirt 26 has at its lower end an inturned concentric flange 28, whose inner periphery is located in slidable relation to the wall 11, so that the space 13 is reduced in area by the thickness of skirt 26 and flange 28 therein, and said reduced space is bounded by wall 11, skirt 26 and flange 28. Therefore valve 24 is normally seated by gravity with its flange 28 upon base 12, and the clearances between the valve and wall 10 and between the inner periphery of flange 28 and wall 11, though said clearances are sufficient only to permit slidable movement to the valve, also serve another function which will be treated of hereinafter.

The vacuum chamber 29 is provided for the operation of valve 24 under the aspiratory tension of the engine, said chamber being bounded by wall 10, skirt 25, surface 20, and an opposed surface 30 which comprises the upper surface of the valve body portion, whereby the rarefaction and suction pull in chamber 29, plus the impinging pressure of ascending fluid against the inclined surface 27, tend to raise said valve.

The suction pull of the engine takes effect in the chamber 29 through the clearance between the cylindrical portion 31 of skirt 25 and the surface 21, this clearance enlarging with the rise of the valve to a given point owing to the special formations of the skirt 25 and the portion 17, whereby the opening

of valve 24 during the low range of engine speed is slow, and is more rapid during the higher range of engine speed.

In Figs. 2, 3, and 4 I have exemplified means whereby the degree of suction drag force applied to the valve 24 is rendered variable by the use of means for regulating the area of the opening which communicates with the valve base.

In Fig. 2 vent means is shown as comprising an orifice 34 provided in portion 17 in communication with a vertical channel 35 extending down the rear surface of said portion and down the rear surface of wall 10, to the base 12, where it communicates with an orifice 35^a extending horizontally to a point beneath the valve 24, and to a vertical opening 36^b, regulated by needle valve 36, for the application of suction drag force to the valve base.

As here shown the valve 36 is provided with a knurled head 36^a by which it may be adjusted to regulate the size of opening 36^b.

Variations within the spirit and scope of my invention are equally comprehended by the foregoing disclosure.

I claim:

In fluid supply means for internal combustion engines, in combination, a control valve, means whereby said valve is caused to open under the suction pull created by the aspiratory operation of the engine, a chamber in which said valve is operable, means of communication including an auxiliary passage whereby said valve is subjected to a drag force, opposed to the lift force, by said suction pull, and means for regulating the degree of drag force to modify its effect upon the valve.

Executed this 3rd day of September, 1924.

FRANK POKORNY.
